EDWIN F. CALLENDER, OF GALESBURG, ILLINOIS, ASSIGNOR OF ONE-HALF TO L. BELLE CALLENDER, OF GALESBURG, ILLINOIS.

INSULATING-TUBE.

1,158,105.

Specification of Letters Patent. Patented Oct. 26, 1915.

Application filed February 9, 1914. Serial No. 817,555.

To all whom it may concern:

Be it known that I, EDWIN F. CALLENDER, a citizen of the United States, and a resident of Galesburg, in the county of Knox 5 and State of Illinois, have invented a new and useful Insulating-Tube, of which the following is a specification.

My invention relates to tubes of that character which are usually formed (by molding) from earthenware or porcelain possessed of electric-insulating properties, and which tubes are employed to permit the passage therethrough of current-carrying wires, the tubes *per se* being first inserted into 10 openings bored through joists, girders, partitions, etc., whereby the tube prevents contact of the live wire therewith.

Tubes of this character as heretofore constructed have not been adequate in their results. One inadequacy is that some of them have been constructed with their outer surfaces, or at least the body portion, forming a perfect cylinder from end to end, or of the same cross sectional areas throughout their 15 lengths. So constructed, there was nothing to prevent them from working out of holes slightly too large. And if the openings for their reception were of such circumference that they fitted very snugly therein they 20 were, owing to their frangible character, frequently broken during placement, owing to driving or forcing them thereinto. Broken pieces of the tube are left to remain in the openings, and in "pulling" the wires the insulation thereon is frequently damaged by 25 said broken pieces, to such extent, in fact, that it is utterly unsafe to use the wires. Furthermore, electricians in working on old buildings often find that tubes have fallen 30 out of the holes and that mice in attempting to pass therethrough have gnawed off the insulation; if the surrounding wood be damp a ground is formed and a fire imminent. The main objection, however, was to 35 their failure, above noted, to retain themselves in the openings provided for their reception, for as soon as they became free therefrom the insulation, (if such there be,) on the wires is very liable to become worn 40 off whereby the live wire comes in contact with the wood or other conductor or inflammable material, resulting not only in frequent loss of property but of lives also.

All holes bored in residence wiring are 45 5/8"—that being "standard". The tubes which are almost universally used are some-

what smaller and are intentionally made to fit loosely within said holes. The reason for this is that it is impossible to construct the tubes of even diameter and circumference 60 throughout their lengths, *i. e.*, minute imperfections will occur in many, and it would be very expensive to throw away all such. Continued walking on floors will cause the tubes to vibrate and eventually drop out of 65 the openings. This is conclusively demonstrated by the fact that in overhauling old houses electricians find that a large proportion of the tubes have worked out of the holes and are hanging suspended on the 70 wire, (which provides a runway therefor,) especially if the holes be bored at an inclination downward, as they generally are.

Other tubes have been provided with longitudinal ridges extending throughout their 75 entire lengths. One of this character cannot be used, in ordinary practice, without breaking it, for what very slight taper is present is at the tip only, and a circle described around the heel portion of the ridges is of no 80 greater diameter than one drawn quite close to the tip. Inasmuch as the ridges begin to cut into the wood as soon as force is applied in placing the tube, the act of forcing it into the opening will cause the weak tip end 85 to collapse or crumble, because of the sudden shock, the length of the ridges, and the lack of taper thereof. I have stated that the length of the ridges is a factor. This is because as soon as they begin cutting, their 90 cutting edges begin to crumble and the broken-off particles adhere to the wood and cause the cuts or clefts to fill and bind the ridges tightly, causing such pressure thereon as is almost certain to crush the tube. 95 And if the hole in the joist be sufficiently large to prevent this, the ridges will have no tendency to bind the tube therein, for their diameter is the same throughout all that portion of the tube which is in contact 100 with the joist.

The main object of my invention is to provide a tube of the character described which may be forced into frictional, wedging contact with any suitable yielding surface, 105 whereby said tube will be self-contained in the opening provided by such surface, with little or no danger of breaking the tube as it is forced thereinto.

Minor objects will be in part obvious and 110 in part specifically pointed out.

In order that the nature of my invention

may be fully understood I have appended hereto a sheet of drawings showing a preferred and also modified embodiments thereof, and in which:

5 Figure 1 is a perspective view of the preferred construction; Fig. 2, a transverse sectional view, taken in the line 2—2 in Fig. 1; Fig. 3, a modification, shown in perspective; Fig. 4, another modification, an end view; Fig. 5, still another modification, shown in perspective; and Figs. 6 and 7, enlarged fragmental details showing respectively an end (or point) view and a plan view of a preferred type or form of fin.

10 Coming now to a detailed description of said drawings and referring to the component portions of the tube by distinguishing reference numerals, 2 designates a tube formed of suitable plastic material, hardened by drying, baking or burning, and comprising a tubular body 3, an annular bead or head 4, and a suitable number of fins 5, preferably tapered, as shown, from the apex *a* of its triangular heel *b* to its point *c*, and tapered also from each base angle *d* to its said point *c*. The edge formed by the line *a c* is preferably as sharp as the nature of the material will permit, in order that it may cut into the wood as it is forced into the opening for the tube. The particular shape or conformation of these fins is not, however, absolutely essential to the invention, considered in its broadest aspect. It is essential, however, that the fins do not extend from end to end of the tube body, for reasons presently stated.

15 In the modification shown in Fig. 3 I have illustrated a tube having no bead, but tapered gradually from end to end on its outer surface and provided with fins 5. To a tube having fins of this particular character, *i. e.*, co-extensive with its length, I make no claim.

20 In Fig. 4 I have illustrated another modification, wherein the tube is tapered and provided with an undulating or corrugated face, the ridges of which correspond to the fins 5 shown in the principal figures.

25 In Fig. 5 I have shown the fins as disconnected from the bead—a space 10 intervening. The fins may be inserts, if preferred.

30 Other modifications which would present themselves to the skilled artisan, but which fall within the general idea of the invention as defined in the appended claims, may be made. It will be noted that the rear ends of the fins on the tubes shown in Figs. 1 and 3 rise to a height equal to that of the bead or head 4—that is to say, a circle circumscribing said ends of the fins is substantially equal in circumference to the circumference of said bead or head. A minute difference, as may occur in the process of manufacture, is immaterial.

35 The advantages gained by making the fins

sharply tapered and extending but a relatively short portion of the length of the tube body, (preferably less than one-half,) are: First: The fins commence cutting only after the plane cylindrical portion of the tube has 70 passed through the joist and cleared the opening therein of the cuttings left from the bit. Second: Being sharply and gradually tapered they cut constantly as they progress. Third: Because of being tapered 75 throughout their lengths and cutting as they progress, the forward portion constantly cuts a passage for the oncoming portion, but cuts it gradually. There is no danger, then, of breakage. Fourth: The operator can 80 judge with certainty when the tube has been driven a sufficient distance—this by merely moving or attempting to move it laterally. Fifth: That portion of the fins which is in 85 frictional contact with the rear edge of the opening in the joist must of necessity bind against the wood, but against an angular edge thereof only, whereas in former tubes (the ridges being the same in height throughout or substantially throughout their 90 lengths) the tips—if they cut at all—cut a constantly increasing way for the portions which followed, and there was absolutely no wedging action such as it is evident is present in and one of the prime and 95 essential features of my invention. Sixth: The front end portion of the tube, being a plane-faced cylinder, thoroughly cleans the hole in the joist as it is driven thereinto, thus preparing it for the admission of the 100 points of the fins. It will be evident that before the fins begin to cut, the fore end of the tube will have passed entirely through the ordinary joist.

Having thus described the nature, objects, 105 purposes and advantages of my invention, I claim as new and desire to secure by Letters Patent the following, *to-wit*:

1. A tube made of frangible insulating material and having a triangular fin on its 110 outer surface, said fin terminating approximately midlength of the body of the tube and being tapered throughout its entire length.

2. A tube made of frangible insulating material having a bead near one of its ends and having a triangular fin tapered toward the end of the tube most remote from said bead, said fin terminating approximately 115 midlength of the body of the tube and the taper being continuous and regular throughout its entire length.

3. An article of the class described made of frangible insulating material and comprising a tubular body having a peripheral head which is also tubular, and having a plurality of fins extending each from said head to substantially the midlength of the body, the rear end of each fin being equal in height 120 to the periphery of said head, each fin being 125

tapered continuously and regularly throughout its length.

4. An article of the class described made of frangible insulating material and comprising a tubular body having a peripheral head which also is tubular, and having a plurality of fins extending each from said head to substantially the midlength of the body, a circle circumscribing the rear ends of said fins being of the same circumference as is the circumference of the head.

5. An article of the class described made of frangible insulating material and comprising a tubular body having an annular head which also is tubular, and having a plurality of continuously and regularly tapered fins the rear ends of which are in contact with said head, a circle circumscribing

the rear ends of the fins being of the same circumference as is the said head.

6. An article of the class described made of frangible insulating material and comprising a body which is tubular throughout its length and having an annular head, and having also a plurality of fins extending each from said head to substantially the midlength of the body, the upper edge or top of each fin touching the extreme outer edge or periphery of said head.

In testimony whereof I hereunto sign my name, at Galesburg, Knox county, Illinois, this 2nd day of February, 1914.

EDWIN F. CALLENDER.
